UNITED STATES PATENT OFFICE

2,547,426

STALL AND MANGER CONSTRUCTION

John D. Youngman, Sleepy Eye, Minn.

Application March 18, 1949, Serial No. 82,210

1 Claim. (Cl. 119—27)

1

This invention relates to a barn structure, and more particularly to a stall for confining and feeding animals therein.

The object of the invention is to provide a stall structure which is ruggedly constructed and which will ensure that an animal will not stray accidentally therefrom.

Another object of the invention is to provide a stall structure whose length can be adjusted as desired, and which is constructed with a minimum of obstructions so that the cleaning of the stall will be greatly simplified.

Still another object of the invention is to provide a stall structure which is so constructed that the animals can be conveniently fed in a novel and efficient manner.

Another object of the invention is to provide a stall structure which is extremely simple and inexpensive to manufacture.

Other objects and advantages will be apparent during the course of the following description, taken with the drawings.

In the drawings, forming a part of this application, and in which like numerals are used to designate like parts throughout the same:

Figure 1 is a side elevational view of the stall structure, according to the present invention;

Figure 2 is a top plan view of the stall structure;

Figure 3 is a front elevational view of the stall;

Figure 4 is a sectional view taken on the line 4—4 of Figure 2.

Referring in detail to the drawings, the numeral 10 designates a horizontal ground surface which may be enclosed by a suitable building or barn (not shown). Projecting upwardly from the ground surface 10 is a pair of spaced parallel vertically disposed posts 11 and 12 which may be fabricated of any suitable material. A horizontally disposed rail 13 extends across the top of the posts 11 and 12 and is secured thereto as by welding.

Positioned rearwardly of the post 11 is a standard 14 which has its lower end embedded in a concrete block 15 which serves to prevent shifting of the standard 14. A similar standard 16 is arranged to the rear of the post 12. A first horizontally disposed guide rail 17 has its front end secured to the post 11 as by welding while the standard 14 supports the rear end of the guide rail 17. A similar horizontally disposed guide rail 17 is extended rearwardly from the other post 12 and has its rear end supported by the other standard 16. An upright 18 projects upwardly from each of the guide rails 17 and is

2

secured thereto, and the upright 18 supports the rear end of a second horizontally disposed guide rail 19 which has its front end secured, as by welding, to the post 11. A similar guide rail 20 extends rearwardly from the other post 12.

Each of the four guide rails have their rear ends open, and a vertically disposed U-shaped partition 21 is mounted for telescopic movement into and out of the rear of the open end of the guide rails 17 and 19. A similar U-shaped partition 22 is mounted for telescopic movement in the rear open end of the guide rail 20 and the guide rail 17 is arranged therebelow. The partitions 21 and 22 permit the length of the stall to be adjusted as desired since the partitions 21 and 22 can be moved longitudinally along the stall. A suitable grating structure may be arranged or formed in the bottom of the stall and a portion of the grating structure is generally indicated by the numeral 23, the grating structure 23 serving to receive manure or other debris whereby the stall can be kept in a clean and sanitary condition at all times.

The ground surface 10 is filled in with cement or concrete 24 in front of the posts 11 and 12, and supported on the concrete slab 24 is an open ended manger of feeding box 25 which may be fabricated of any suitable material. A board or plank 26 extends along the lower ends of the posts 11 and 12 and is secured thereto, there being a cut-out 27 arranged in the sides of the manger 25 for receiving the plank 26 when the manger is in normal position. The manger 25 is adapted to receive hay and feed, or the like, and the manger 25 is detachably connected to the posts 11 and 12 so that the area in front of the stall can be cleaned readily by removing the manger as desired. Thus, a bracket 27 may be secured to each of the posts 11 and 12 in any suitable manner, such as by rivets, or the like, and a headed pin 28 projects through the bracket 27 and through the upper ends of the manger 25, there being a suitable cotter pin 29 for maintaining the parts in assembled relation.

Arranged adjacent the top of the beam 11 and secured thereto is a bracket 30, and a similar bracket 31 is arranged adjacent the top of the beam 12 and secured thereto. A horizontally disposed brace 32 projects forwardly from the bracket 30 and is secured thereto, there being a similar horizontally disposed brace 33 projecting forwardly from the other bracket 31 and secured thereto. Extending between the outer projecting ends of the braces 32 and 33 is a horizontally disposed rod 34. A pair of U-shaped strap iron

hanger members 35 depend from the rod 34 and the hanger members each have a cotter pin 44 extending therethrough. Suitable securing elements such as rivets 45 secure the lower ends of the straps 35 to the gate structure 36.

The gate structure 36 comprises a pair of horizontally disposed spaced parallel straps 37 and a plurality of vertically disposed spaced parallel slats 38 which are secured to the straps 37 by suitable securing elements, such as nails or rivets 39. The gate structure 36 is mounted for swinging movement about a horizontal axis. Thus, when feed, such as hay or feed is loaded into the manger 25, the gate structure 36 is pivoted back to the dotted line position shown in Figure 1, to facilitate the placing of the feed in the manger. After the feed has been positioned in the manger 25, the gate 36 will return to its normal position shown in solid lines, Figure 1, whereby the animal in the stall can consume or eat the food in the manger 25 since the gate 36 is spaced a sufficient distance in front of the posts 11 and 12.

From the foregoing, it is apparent that a stall structure has been provided which can be adjusted longitudinally in order to increase the length thereof as desired. Thus, the partitions 21 and 22 can be moved in and out of the guide rails, there being suitable apertures 40 arranged in spaced relation along each of the guide rails, and the apertures 40 are adapted to register with apertures 41 which are arranged in the legs of the U-shaped partitions 21 and 22. A suitable pin 42 is adapted to be inserted through a pair of the registering apertures 40 and 41 so as to maintain the partitions 21 and 22 immobile in their adjusted position. Further, the stall is constructed so that the feeding box 25 is positioned at a convenient location whereby it can be readily filled by pivoting the gate structure 36 rearwardly and after the feed has been properly positioned in the manger 25, the gate 36 will hang so that the animal in the stall can readily and comfortably eat the food from the manger 25. Further, the manger is detachably connected to the posts 11 and 12 whereby the manger 25 can be quickly attached to the posts or else the manger 25 can be detached from the posts in order to provide

ample passageway in front of the stall or in order to clean the area in front of the stall. It is to be understood that the stalls may be arranged so that a plurality of the stalls are positioned in side-by-side relation with respect to each other in a barn so that any desired number of animals can be confined therein.

As many embodiments may be made of this inventive concept, and as many modifications may be made in the embodiment hereinbefore shown and described, it is to be understood that all matter herein is to be interpreted merely as illustrative and not in a limited sense.

I claim:

A manger for cattle stalls including spaced side partitions, posts rising from and above the rear ends of said partitions, a relatively deep box-like feed container closing the rear end of the space between said partitions, an arm extending horizontally rearward from adjacent the upper end of each of said posts, and a guard gate pivotally supported from the free ends of said arms and depending into said container medially between the front and rear sides thereof, said guard gate being adapted to be swung forwardly to provide clearance for the placing of feed into said container from the rear side thereof and thereafter return to its normal position to prevent the nosing of the feed rearwardly from the container by an occupant of the stall.

JOHN D. YOUNGMAN.
